UNITED STATES PATENT OFFICE

RUTH D. MAURER AND HERBERT D. JOYCE, OF NEW YORK, N. Y., ASSIGNORS TO RUTH D. MAURER CORPORATION, OF NEW YORK, N. Y., A CORPORATION OF NEW YORK

DESIGN FOR A BOTTLE

Application filed March 28, 1930. Serial No. 35,059. Term of patent 14 years.

To all whom it may concern:

Be it known that we, RUTH D. MAURER, a citizen of the United States of America, and HERBERT D. JOYCE, a subject of the Kingdom of Great Britain, and both residents of New York city, New York, United States of America (whose post-office address is 15 West 46th Street, New York city, New York), have invented a new, original, and ornamental Design for a Bottle, of which the following is a specification, reference being had to the accompanying drawing, forming part thereof.

We claim:

The ornamental design for a bottle, as shown.

Dated at New York, N. Y., this 21st day of March, 1930.

RUTH D. MAURER.
HERBERT D. JOYCE.
